United States Patent Office

Des. 186,749
Patented Nov. 24, 1959

186,749

CEILING MOUNTED ELECTRICAL HEATER

Harold H. Ford, Claremont, Calif., assignor to Emerson-Pryne Company, Pomona, Calif., a corporation of Delaware

Application February 9, 1959, Serial No. 54,521

Term of patent 14 years

(Cl. D81—10)

Fig. 1 is a side elevation of a ceiling mounted electrical heater showing my new design.

Fig. 2 is a bottom plan thereof.

Fig. 3 is a partial vertical cross-section thereof as on line 3—3 of Fig. 2.

I claim:

The ornamental design for a ceiling mounted electrical heater, as shown.
